RELOOPING NEEDLE

Walter O. Runcie, Lima, Peru

Application October 16, 1950, Serial No. 12,585

Term of patent 7 years

(Cl. D47—5)

To all whom it may concern:

Be it known that I, Walter Osborne Runcie, a citizen of no country, and a resident of Lima, Peru, have invented a new, original, and ornamental Design for a Relooping Needle, of which the following is a specification, reference being had to the accompanying drawing, forming a part thereof.

In the drawing:

Figure 1 is a side elevational view of a relooping needle showing my new design.

Figure 2 is an exploded side elevational view of the same.

Figure 3 is an end elevational view of the cap.

Figure 4 is an end elevational view of the needle with the cap removed.

I claim:

The ornamental design for a relooping needle, as shown.

WALTER O. RUNCIE.
